COSTUMER

Luther G. Simjian, Stamford, Conn., assignor to
 The Reflectone Corporation, Stamford, Conn.,
 a corporation of Connecticut

Application February 12, 1949, Serial No. 76,129

4 Claims. (Cl. 211—178)

1

This invention relates to an expandable costumer of the type adapted to hold a man's suit and other parts of apparel. Costumers of the particular class are quite old and well known in the art, but they are generally quite complex in construction and require considerable storage room. It is the object of my invention to contribute a simple standing costumer that may readily be folded into a compact unit, with the further feature that when so folded, it stands on legs and is self-supporting.

As a feature of my invention I form my costumer of two frames, a main frame and a secondary frame, the secondary frame being movable into what might be termed nested relation relatively to the main frame. As a particular feature of the invention the secondary frame is yieldingly held in nested position, and when in such nested position, all its parts preferably lie within extensions of the main frame.

As a further feature of the invention, the main and secondary frames are equipped with legs that coact to support the costumer in an expanded and also in a folded position. As a particular feature of this part of the invention, when the secondary frame is moved outwardly of the main frame, a supporting leg movable with the secondary frame is positioned to support better the entire costumer. As a further particular feature of this part of the invention, the secondary frame carries a coat rack that is movable into an extended vertical position above both the main and secondary frames for supporting a coat, a necktie, a shirt, etc.

A further feature of the invention resides in the utilization of locking or latching means for locking the coat rack in a vertically extended position, and thereby locking in an expandable position the entire costumer including the main and secondary frames.

As a further feature of the invention, the secondary frame carries therewith a shoe rack bar that is moved therewith into a position vertically above and horizontally displaced from a shelf on the main frame. Thereby, when the secondary frame is in expanded relation to the main frame, the shoe rack bar is effective to support a pair of shoes thereon in coaction with the shelf of the main frame.

As a still further feature of the invention, the main frame carries a trouser support bar movably mounted thereon and adapted for movement outwardly of the main frame and inwardly thereof. In its outward position the trouser support bar may have the trousers draped thereover,

2

after which it is pivotally movable inwardly of the main frame to drape the trousers further over an additional bar carried by the main frame so as to better support the trousers and to hold the trousers against sliding release movement.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures within the scope of the appended claims for carrying out the several purposes of my invention.

20 Referring now to the drawings, Fig. 1 is a perspective view of my costumer in extended relation with several articles of apparel shown in phantom supported thereon. Fig. 2 is a view taken along lines 2—2 of Fig. 1. Fig. 3 is a partial vertical section showing the costumer in folded relation. Fig. 4 is an enlarged sectional view of the latch and its relation to the coat rack. Fig. 5 is a view looking from the right toward Figs. 2 and 4 with a part of the structure in section for clarification thereof.

Referring now more particularly to the drawings, the main frame of my invention is designated by reference numeral 10 and includes an upper tray 11 and legs 12. The legs 12 are reinforced near the lower ends thereof by a shelf 13 and intermediate thereof by a bar 14 securely dowelled thereto. A bracket 15 is pivoted at 16 to each leg 12 of the main frame, the two brackets carrying a trouser support bar 17. It is obvious that the support bar may readily be moved from its position of Fig. 1 and its solid line position of Fig. 2, to its dotted line position of Fig. 2.

The secondary frame of my invention is designated generally by reference numeral 18 and comprises as a part thereof a vertical bar 19. This bar 19 is pinned at 20 to a dowel 21 bearing in the shelf 13 and thereby mounting the bar 19 for rotary movement relatively to the said shelf. The dowel 21 has pinned thereto at 22 a foot 23 so that the said foot 23 rotates with the bar 19 in the axis of the bar 21, the foot 23 really forming thereby a part of secondary frame 18. At its upper end the bar 19, as best illustrated in Fig. 5, carries a wood screw 24 the head 25 of which bears somewhat freely in an opening 25a of a

steel plate 26 secured by one or more wood screws 27 to the underside of the tray 11. The head 25 of the screw 24, through its contact with opening 25a, thereby acts as a bearing member relatively to the steel plate 26 whereby to mount the upper end of the bar 19 for pivotal movement relatively to the tray 11 of the main frame 10. The axis of screw 24 is in vertical alignment with the axis of the dowel 21 so that the secondary frame rotates about the screw 24 and dowel 21 relatively to the main frame, all as will now be obvious.

For yieldingly holding the bar 19 and secondary frame 18 in the position of Figs. 1 and 2, or in the position of Fig. 3, the bar 19 is drilled at 28 for a spring 29 pressing against a ball 30. The ball 30 coacts with holes 31 and 32 in the steel plate 26 to maintain bar 19 yieldingly in the position of Fig. 5 or in a position 180° therefrom, in which position the hole 32 will be aligned relatively to the ball 30.

The coat rack portion of my invention is designated by reference numeral 33 and is preferably in the form of a curved wood bar substantially the same in width as the bar 19. A pair of metal straps 34 is secured to the opposite sides of the coat rack portion 33 as is quite readily seen in Figs. 3 and 5, said straps mounting the coat rack for pivotal movement on the bar 19 by a pair of wood screws 35 coacting with the straps 34 in the same manner as the screws 24 coact with steel plate 26. In this way, the coat rack portion 33 is rotatable from its position of Fig. 3 relatively to the secondary frame to its position of Fig. 2 relatively to said frame.

The tray 11 has secured thereto a small latch casing 36 in which is pivoted a latch bolt 37 about an axis 38. A spring 39, as best seen in Fig. 4, tends to rotate the latch bolt 37 in a clockwise direction. A plunger 40, equipped with a head 41, extends from the latch casing 36 and through a bore of the wall of tray 11 into the tray 11 as best seen in Figs. 1 and 2. Obviously, by inward pressing of the plunger 40 the latch bolt 37 is moved counter-clockwise against the force of the spring 39 to a release position.

Coacting with the latch bolt 37 is a strike plate 42 held by a screw 43 on the coat rack 33. The coat rack 33 is formed with an opening 44 whereby when the coat rack swings upwardly on the axis of the screws 35 relatively to the bar 19, the opening 44 will be aligned with the casing 36. The strike plate 42 will enter into engagement with the latch bolt 37 so as to hold the coat rack 33 in its position of Figs. 1 and 2. The latch bolt 37 not only holds the coat rack 33 in position, but maintains the costumer in its proper extended relation as it is now impossible to rotate bar 19 on its pivot axis.

The vertical bar 19 of the costumer is equipped with a bracket 45 carrying a shoe rack bar 46. When the secondary frame is nested within the main frame, the shoe rack bar 46 occupies the position illustrated in Fig. 3. When the secondary frame is rotated to its position of Fig. 2, the shoe rack bar 46 is vertically above and horizontally offset relatively to the shelf 13 so that a shoe S, shown in phantom in Fig. 1, may readily be placed in support position on the costumer.

Considering the construction generally once again, it will be noted that in Fig. 3 the secondary frame 18 is shown fully nested within the main frame. In order to use the costumer, the bar 19 is first rotated to the position of Fig. 2, carrying the shoe rack bar into the position of

Fig. 1 and bringing the foot 23 into better supporting relation to the costumer, all as will be quite obvious. Now, the coat rack 33 may be swung upwardly and into the position of Fig. 2 where it is latched by bolt 37 to hold the entire costumer in the particular extended position illustrated. The user of the costumer may now apply a coat C to the coat rack with a necktie or shirt hanging on the hook 47. Trousers may be placed on trouser support bar 17 after the said support bar has been moved from the position of Fig. 3 into the full line position of Fig. 2. Now by moving the trouser support bar 17 from its full line position of Fig. 2 into the dotted line position, the trousers will be draped between the bar 17 and the bar 14 whereby not readily to slide off the said bars. As earlier described, the shoes may be placed in the position illustrated in phantom in Fig. 1 for support by the bar 46 and the shelf 13. Other articles may be deposited in the tray 11 so as to be readily available.

I believe that the construction and operation of my invention will now be readily apparent to those skilled in the art.

I claim:

1. In a combination of the class described, a main frame having a leg portion and adapted to stand vertically on said leg portion, a secondary frame having a leg, a member extending horizontally from said main frame, means pivoting said secondary frame to said horizontally extending member on a vertical pivot offset from said main frame and intermediate the ends of said main frame for pivotal movement between a use position in which said secondary frame is out of nested relation with respect to said main frame, and a non-use position in which said secondary frame is in nested relation with respect to said main frame under said horizontally extending member, the leg of said secondary frame stabilizing both said frames when said secondary frame is rotated out of nested relation to said main frame, a coat rack pivoted to said secondary frame on a horizontal pivot and adapted to hang on said pivot in a position between said frames under said horizontally extending member when said frames are nested, said coat rack being positioned on said secondary frame for rotating bodily on said vertical pivot coaxially with said secondary frame, and means for locking said coat rack in a vertical position on its pivot to form a vertical extension of said secondary frame above said horizontally extending member when said secondary frame is moved on its pivot out of nested relation to said main frame.

2. In a combination of the class described, a main frame having a leg portion and adapted to stand vertically on said leg portion, a secondary frame having a leg, a member extending horizontally from said main frame, means pivoting said secondary frame to said horizontally extending member on a vertical pivot offset from said main frame and intermediate the ends of said main frame for pivotal movement through 180° between a use position in which said secondary frame is out of nested relation with respect to said main frame, and a non-use position in which said secondary frame is in nested relation with respect to said main frame under said horizontally extending member, the leg of said secondary frame stabilizing both said frames when said secondary frame is rotated out of nested relation to said main frame, a coat rack pivoted to said secondary frame on a horizontal pivot and adapted to hang on said pivot in a

position between said frames when said frames are nested, said coat rack being positioned on said secondary frame for rotating bodily on said vertical pivot coaxially with said secondary frame, and means for locking said coat rack in a vertical position on its pivot to form a vertical extension of said secondary frame above said horizontally extending member when said secondary frame is moved on its pivot out of nested relation to said main frame.

3. In a combination of the class described, a main frame having a leg portion and adapted to stand vertically on said leg portion, a secondary frame having a leg, a tray extending horizontally from said main frame, means pivoting said secondary frame to said tray on a vertical pivot offset from said main frame for pivotal movement between a use position in which said secondary frame is out of nested relation with respect to said main frame, and a non-use position in which said secondary frame is in nested relation with respect to said main frame under said tray, the leg of said secondary frame stabilizing both said frames when said secondary frame is rotated out of nested relation to said main frame, a coat rack pivoted to said secondary frame on a horizontal pivot and adapted to hang on said pivot under said tray in a position between said frames when said frames are nested, said coat rack being positioned on said secondary frame for rotating bodily on said vertical pivot coaxially with said secondary frame, and means for locking said coat rack in a vertical position on its pivot to form a vertical extension of said secondary frame above said tray when said secondary frame is moved on its pivot out of nested relation to said main frame.

4. In a combination of the class described, a main frame having a leg portion and adapted to stand vertically on said leg portion, a secondary frame having a leg, a tray extending horizontally

from said main frame, means pivoting said secondary frame to said tray on a vertical pivot offset from said main frame and intermediate the ends of said main frame for pivotal movement through 180° between a use position in which said secondary frame is out of nested relation with respect to said main frame, and a non-use position in which said secondary frame is in nested relation with respect to said main frame under said tray, the leg of said secondary frame stabilizing both said frames when said secondary frame is rotated out of nested relation to said main frame, a coat rack pivoted to said secondary frame on a horizontal pivot and adapted to hang on said pivot under said tray in a position between said frames when said frames are nested, and means for locking said coat rack in a vertical position on its pivot to form a vertical extension of said secondary frame above said tray when said secondary frame is moved on its pivot out of nested relation to said main frame.
